DOLL'S HEAD CONSTRUCTION

Nunzio Paganello, Brooklyn, N. Y.

Application April 26, 1934, Serial No. 722,431

10 Claims. (Cl. 46—40)

This invention relates to an improvement in doll's head construction, and more particularly to the mounting of the eyes. One object of the invention is to provide means by which the eyes may be readily and quickly positioned in their sockets or removed therefrom without the aid of skilled labor.

Another object is to provide a mounting for the eye carrying device which may be permanently secured to the doll's head immediately after the head is molded and before the head is completely finished.

Another object is to provide a mounting for the eye carrying device which will permit of a vertical adjustment as well as a lateral movement of the eye carrying device.

Another object is to provide certain improvements in the form, construction and arrangement of the several parts whereby the above named and other objects may effectively be attained.

A practical embodiment of my invention is represented in the accompanying drawing, in which

Fig. 1 represents a vertical section of the doll's head looking toward the front interior wall and showing my improved eye mounting structure applied thereto;

Fig. 2 represents a vertical section taken in the plane of the line II—II of Fig. 1, looking in the direction of the arrows;

Fig. 3 represents a vertical section taken in the plane of the line III—III of Fig. 1, looking in the direction of the arrows; and

Fig. 4 represents a horizontal section taken in the plane of the line IV—IV of Fig. 1, looking in the direction of the arrows.

The doll's head is denoted by 1 and is provided with the usual eye sockets 2, 3, between which are formed recesses 4, 5 and 6 disposed in vertical alignment. The mounting comprises a flat base 7 having rearwardly extended ears 8, 9 disposed along the side edges thereof. The upper and lower edges of the base are bent forwardly and toward each other to form retaining members 10, 11 which are cemented in the recesses 4 and 5 respectively, and thereby secure the mounting permanently in position between the sockets 2, 3. The ears 8, 9 have formed therein horizontally disposed slots 12; the portions adjacent the base are relatively wide and have straight vertical walls 13. The slots 12 are tapered toward the rear and have restricted openings 14 extending downwardly therefrom to form entrances and exits to and from the slots. The lower edges of the ears 8, 9 are curved at 15

toward the openings 14 to serve as guides thereto.

The eye carrying device comprises a horizontally disposed shaft 16 having secured at opposite ends semi-spherical eyes 17, 18 which may be adjusted rotatably and longitudinally thereon in any well-known or approved manner. This shaft 16 is mounted to rotate in the slots 12 in the ears 8, 9 and arranged to be adjusted vertically along the walls 13 of the slots so that the eyes may be properly located in their sockets.

A counter balance 19 is secured to the shaft 16 by means of depending arms 20, 21 which are disposed adjacent the ears 8, 9 respectively, and serves to control the position of the eyes 17, 18 with respect to the sockets 2, 3 in the head.

An element 22 formed of a relatively thin strip of metal is disposed to move between the ears 8, 9 toward and away from the base 7, and an elongated recess 23 is developed in the strip in position to engage the shaft 16 and hold it against the vertical walls 13 of the slots 12 in any adjusted position, so that the eyes will oscillate in their sockets 2, 3. A hollow rivet 24 or other suitable means is cemented in the recess 6 so as to extend outwardly therefrom in position to receive the upper end 25 of the element 22 to support it in its position between the ears. The lower end 26 of the element 22 is curved rearwardly and downwardly to extend beyond the ears and in an opposite direction to the curvature 15 of the lower edges of the ears so that, when the eye carrying device is to be assembled in the mounting, the shaft 16 will be caused to ride on the curved edges 15 of the ears 8, 9 into contact with the curved end 26 of the element 22, which movement of the shaft will actuate the element rearwardly past the restricted openings 14 in the ears so that the shaft 16 will be free to enter the restricted openings 14 of the slots 12 in the ears.

When the shaft has passed through the restricted openings 14, the element will tend to force it forwardly to its position against the vertical walls 13 of the slots 12 and, as the eyes on the shaft are adjusted to their sockets, the shaft will be received in the elongated recess 23. While the element 22 has a slight resiliency which tends to force the shaft against the vertical walls 13 of the slots 12, it is not sufficient to maintain the shaft in such position against any unintentional jarring action which might be given the head to cause the eyes to be displaced from their sockets, and in order to resist such action, the curved lower end 26 of the element 22 is bent upwardly at 27 in position to be engaged by the free end of

a flat spring 28, the upper end of which is attached to the head by the rivet 24 which also secures the element 22 to the head. This spring 28 not only holds the element in position between the ears but it exerts pressure on the upturned end 27 of the element which in turn causes the walls of the recess 23 to engage the shaft 16 and hold it against the vertical walls 13 of the slots 12 and the eyes in their sockets. Any slight pressure on the eyes from the outside through their sockets will be consumed by the yieldability of the element between the recess 23 and the upturned end 27.

When it is desired to remove the eye carrying device for the purpose of replacement or adjustment, the curved end 26 of the element 22 is manipulated against the tension of the spring 28 so that the shaft 16 may be released from the recess 23 when it registers with the restricted openings 14 in the ears 8, 9.

From the foregoing, it will be seen that any undue force or strain which may be transmitted to the eye carrying device cannot be transferred to the mounting, since any strain placed on the eye carrying device is absorbed by the element 22 and spring 28 which is entirely free of any rigid connection with the mounting, thereby obviating the breaking away of the cementitious fastening means of the mounting.

To limit the rocking movement of the shaft 16 in one direction, stops 29, 30 extend upwardly from the shaft and are arranged to be brought into engagement with the inner wall of the head. The shaft 16 is also limited in its rocking movement in the other direction by the counterbalance 19 which engages the inner wall of the head, as shown in Figs. 2 and 3.

It is evident that various changes may be resorted to in the form, construction and arrangement of the several parts without departing from the spirit and scope of my invention; and hence, I do not intend to be limited to the details herein shown and described, except as they may be included in the claims.

What I claim is:

1. In combination with a hollow doll's head having eye sockets therein, a member secured to the interior of the head between the sockets and provided with ears projecting rearwardly therefrom in spaced relation, a horizontally disposed shaft rotatably mounted in said ears and having semispherical eyes secured thereto in position to coact with the sockets, a separate element disposed above said member in position to engage the shaft between the ears for maintaining the eyes in their sockets, and a spring means attached to the head independent of the member and adapted to contact with said element to yieldingly hold the element in position between the ears.

2. In combination with a hollow doll's head having eye sockets therein, a member secured to the interior of the head between the sockets and provided with ears projecting rearwardly therefrom in spaced relation, a horizontally disposed shaft rotatably mounted in said ears and having semi-spherical eyes secured thereto in position to coact with the sockets, a separate element fixed to the head above said member in position to overhang the member and engage the shaft between the ears for maintaining the eyes in their sockets, and a spring means attached to the head independent of the member and adapted to contact with said element to yieldingly hold the element in position between the ears.

3. In combination with a hollow doll's head having eye sockets therein, a member secured to the interior of the head between the sockets and provided with ears projecting rearwardly therefrom in spaced relation, said ears having open slots therein, a horizontally disposed shaft rotatably mounted in said slots and having semi-spherical eyes secured thereto in position to coact with the sockets, a separate element disposed above said member in position to engage the shaft between the ears for maintaining the eyes in their sockets, and a spring means attached to the head independent of the member and adapted to contact with said element to yieldingly hold the element in position between the ears.

4. In combination with a hollow doll's head having eye sockets therein, a member secured to the interior of the head between the sockets and provided with ears projecting rearwardly therefrom in spaced relation, said ears having open slots therein, a horizontally disposed shaft rotatably mounted in said slots and having semi-spherical eyes secured thereto in position to coact with the sockets, a separate element fixed to the head above said member in position to overhang the member and engage the shaft between the ears for maintaining the eyes in their sockets, and a spring means attached to the head independent of the member and adapted to contact with said element to yieldingly hold the element in position between the ears.

5. In combination with a hollow doll's head having eye sockets therein, a member secured to the interior of the head between the sockets and provided with ears projecting rearwardly therefrom in spaced relation, said ears having relatively wide elongated slots and restricted openings extending downwardly therefrom, a horizontally disposed shaft rotatably mounted in said wide portion of the slots and having semi-spherical eyes secured thereto in position to coact with the sockets, a separate element disposed above said member in position to engage the shaft between the ears for maintaining the eyes in their sockets, and a spring means attached to the head independent of the member and adapted to contact with said element to yieldingly hold the element in position between the ears.

6. In combination with a hollow doll's head having eye sockets therein, a member secured to the interior of the head between the sockets and provided with ears projecting rearwardly therefrom in spaced relation, said ears having relatively wide elongated slots and restricted openings extending downwardly therefrom, a horizontally disposed shaft rotatably mounted in said wide portion of the slots and having semi-spherical eyes secured thereto in position to coact with the sockets, a separate element fixed to the head above said member in position to overhang the member and engage the shaft between the ears for maintaining the eyes in their sockets, and a spring means attached to the head independent of the member and adapted to contact with said element to yieldingly hold the element in position between the ears.

7. In combination with a hollow doll's head having eye sockets therein, a member secured to the interior of the head between the sockets and provided with ears projecting rearwardly therefrom in spaced relation, said ears having relatively wide elongated slots and restricted openings extending downwardly therefrom, a horizontally disposed shaft rotatably mounted in said wide portion of the slots and having semi-spherical eyes secured thereto in position to coact with the sockets, a separate element fixed to the head above said member in position to overhang the member and engage the shaft between the ears for maintaining the eyes in their sockets, and a spring means attached to the head independent of the member and adapted to contact with said element to yieldingly hold the element in position between the ears.

ical eyes secured thereto in position to coat with the sockets, a separate element having a longitudinally disposed elongated recess arranged to engage the shaft between the ears for allowing vertical adjustment and maintaining the eyes in their sockets, and a spring means attached to the head independent of the member and adapted to contact with said element to yieldingly hold the element in position between the ears.

8. In combination with a hollow doll's head having eye sockets therein, a member secured to the interior of the head between the sockets and provided with ears projecting rearwardly therefrom in spaced relation, said ears having relatively wide elongated slots and restricted openings extending downwardly therefrom, a horizontally disposed shaft rotatably mounted in said wide portion of the slots and having semi-spherical eyes secured thereto in position to coat with the sockets, a separate element fixed to the head above said member in position to overhang the member and having a longitudinally disposed elongated recess arranged to engage the shaft between the ears for allowing vertical adjustment and maintaining the eyes in their sockets, and a spring means attached to the head independent of the member and adapted to contact with said element to yieldingly hold the element in position between the ears.

9. In combination with a hollow doll's head having eye sockets therein, a member secured to the interior of the head between the sockets, said member comprising a flat base having rearwardly extended ears disposed along the vertical side edges thereof, said ears having relatively wide slots and restricted openings extending downwardly therefrom, the lower edges of said ears being curved toward said restricted openings, a horizontally disposed shaft removably mounted in said slots in the ears and having semi-spherical eyes secured thereto in position to coat with the sockets, a separate element hav-

ing a longitudinally disposed elongated recess arranged to engage the shaft between the ears for allowing vertical adjustment and maintaining the eyes in their sockets, the lower end of said element being curved rearwardly and downwardly to extend beyond the ears, and a spring means attached to the head independent of the base of the member and adapted to contact with said element to yieldingly hold the element in position between the ears, whereby the curved lower edges of the ears and the curved portion of the element coat to guide the shaft into the restricted openings in the ears when being assembled.

10. In combination with a hollow doll's head having eye sockets therein, a member secured to the interior of the head between the sockets, said member comprising a flat base having rearwardly extended ears disposed along the vertical side edges thereof, said ears having relatively wide slots and restricted openings extending downwardly therefrom, the lower edges of said ears being curved toward said restricted openings, a horizontally disposed shaft removably mounted in said slots in the ears and having semi-spherical eyes secured thereto in position to coat with the sockets, a separate element fixed to the head above said base of the member in position to overhang the base and having an elongated recess arranged to engage the ears for allowing vertical adjustment and maintaining the eyes in their sockets, the lower end of said element being curved rearwardly and downwardly to extend beyond the ears, and a spring means attached to the head independent of the base of the member and adapted to contact with said element to yieldingly hold the element in position between the ears, whereby the curved lower edges of the ears and the curved portion of the element coat to guide the shaft into the restricted openings in the ears when being assembled.

NUNZIO PAGANELLO.
